EMBROIDERING AND CORDING ATTACHMENT FOR SEWING MACHINES

Esteban Prato, Caracas, Venezuela, assignor to
The Singer Manufacturing Company, Elizabeth, N. J., a corporation of New Jersey

Application March 14, 1936, Serial No. 68,831

9 Claims. (Cl. 112—139)

This invention relates to embroidering and cording attachments for sewing machines and has for an object to provide a cording attachment of simplified construction which is adapted to handle one or more cords of various sizes, particularly small sizes, and present such cord or cords with certainty to the sewing machine needle. The invention also aims to provide for the ready adjustment of the attachment to suit the particular cord or cords being handled thereby.

With the above and other objects in view, as will hereinafter appear, the invention comprises the devices, combinations, and arrangements of parts hereinafter set forth and illustrated in the accompanying drawings of a preferred embodiment of the invention, from which the several features of the invention and the advantages attained thereby will be readily understood by those skilled in the art.

In the accompanying drawings, Fig. 1 is a perspective view of an attachment embodying the invention and applied to the presser-bar of a sewing machine. Fig. 2 is a front elevation of the attachment. Fig. 3 is a side elevation of the attachment. Fig. 4 is a bottom plan view of the foot-portion of the attachment. Fig. 5 is a large scale longitudinal vertical section through the foot-portion of the attachment. Fig. 6 is a section on the line 6—6, Fig. 5, and Fig. 7 is a plan view of a duplex corded seam as produced by the attachment.

In the drawings 1 represents the conventional taper-pointed sewing machine needle, which reciprocates vertically through the needle-hole 2 in the throat-plate 3 and cooperates with the usual loop-taker mechanism (not shown) below the throat-plate to form stitches. The work is fed by the usual feed-dog 4.

The present embodiment of the invention comprises a presser-foot 5 which is formed with a shank 6 adapting it for attachment by the screw 6' to the usual sewing machine presser-bar 7. The presser-foot 5 preferably has a tread-portion formed with spaced toes 8, 9 between which is the needle-opening or slot 10. The toe 9 and heel 9' are preferably thickened vertically relative to the toe 8 to form the vertical side wall 9^a and rear wall 9^b.

The shank 6 is preferably formed with an arm 12 having a forwardly extending branch arm 12' formed with the multiple cord-guiding and tensioning apertures 13. Integral with and rising from the arm 12 is a vertical supporting branch arm 14 to the upper end of which the comparatively long cord-guiding leaf-spring 15 is prefer-

ably adjustably secured by means of the conventional screw and slot means 16. The leaf-spring 15, in addition to being long, is quite thin and resilient; being preferably about .015 inch thick. It extends downwardly from the screw 16, which is higher than the shank 6, at an inclination to the vertical, preferably as shown in Fig. 2, and terminates in the slot 10 between the presser-foot toes 8 and 9. The lower end-portion of the leaf-spring 15 is preferably bent or curved cylindrically about an axis x, Fig. 6, extending horizontally in the direction of seam formation, to provide a cylindrically convex cord-positioning face 17 which is disposed in the path of reciprocation of the needle 1 so as to be engaged and slightly displaced by the needle. The rear edge 15^a of the leaf-spring member should preferably be set close to but not touching the rear presser-foot wall 9^b, which latter is disposed preferably closely in rear of the needle-path, as shown in Figs. 3 and 5. The leaf-spring 15 is also preferably provided with the cord-guiding apertures 18 through which one or more cords 19 are led at a downward inclination along and helically of the cylindrically convex face 17, Fig. 5, of the leaf-spring member 15 and under the heel 9' of the presser-foot.

An adjusting screw 21 carried by the vertical arm 14 bears against the leaf-spring 15 and regulates the lateral position of the effective lower end thereof relative to the sewing machine needle 1. The screw 21 may also serve to regulate the tension on the leaf-spring 15 in case such regulation is deemed desirable in sewing cords of certain thicknesses or textures.

In the operation of the above described preferred embodiment of the invention, the screw 21 is ordinarily adjusted so that the point of the needle 1 lightly strikes and laterally displaces the leaf-spring member 15. By referring to Fig. 6 it will be observed that, on account of the convex face 17 of the leaf-spring, the point of contact 22 between the conical side wall of the needle and such face lies above the needle-point which is clear of the face 17 and hence penetrates with certainty the cord or cords 19 lying thereagainst.

Where two cords 19 are used, they are usually secured in offset superposed relation to the body-fabric 23 by the single line of straight-away stitches 24. Where cords of contrasting colors are used, very unusual and attractive cording effects may be readily produced. The tension applied to the cords 19 by the lead-in guide apertures 13 is a very light one; just enough to prevent slackening of the cord or cords during the sewing op-

eration and to maintain the cord or cords against the convex face 17 of the leaf-spring member 15.

The invention is not to be understood as limited to the details of construction and relative arrangements of parts shown and described as such details and relative arrangements may obviously be modified without departure from the invention.

Having thus set forth the nature of the invention, what I claim herein is:—

1. The combination with a reciprocatory needle, work-feeding means and a presser-foot, of cord-guiding means disposed in the normal path of reciprocation of said needle so as to be engaged by the latter said cord-guiding means being yieldable away from the needle-path to such a degree as to be deflected by said needle in the down-stroke of the latter.

2. The combination with a reciprocatory needle, work-feeding means and a presser-foot, of cord-guiding means having a cord-guiding surface disposed in the normal path of reciprocation of said needle so as to be engaged by the latter, said cord-guiding means being yieldable away from the needle-path to such a degree as to be deflected by said needle in the down-stroke of the latter.

3. In a sewing machine, the combination with a reciprocatory eye-pointed needle, of means to present a cord to said needle comprising a member having a cord-guiding surface which is disposed in the normal path of reciprocation of said needle and is curved about an axis extending in the direction of seam-formation, and means for leading the cord helically of said surface so that the pointed needle in grazing the latter will penetrate the cord.

4. The combination with a reciprocatory needle, of means for positioning a cord for penetration by said needle, said means comprising a cord-positioning leaf-spring member disposed in the normal path of reciprocation of said needle and yieldable laterally of the needle-path when engaged by said needle.

5. The combination with a reciprocatory needle, of means for positioning a cord for penetra-

tration by said needle, said means comprising a support, a leaf-spring member mounted on said support and having a free cord-positioning face-portion disposed in the normal path of reciprocation of said needle and yieldable laterally of the needle-path under the influence of said needle.

6. The combination with a reciprocatory needle, of means for positioning a cord for penetration by said needle, said means comprising a support, a leaf-spring member mounted on said support and having a free cord-positioning face-portion disposed in and yieldable laterally of the needle-path, said member having one or more cord-guiding apertures therein in advance of said face-portion.

7. The combination with a reciprocatory needle, of means for positioning a cord for penetration by said needle, said means comprising a cord-positioning leaf-spring member disposed in the normal path of reciprocation of said needle and yieldable laterally of the needle-path under the influence of said needle, and an adjusting screw bearing upon said leaf-spring member.

8. The combination with a reciprocatory conically pointed needle, and feeding mechanism, of a leaf-spring member having a cord-positioning convex face yieldable laterally of the line of seam-formation under the influence of said needle and disposed in the path normal of said needle, and means for leading a cord along said convex face and across the needle-path at an elevation below the point of tangency of the conical surface of the needle point and said face.

9. A cording attachment for sewing machines comprising a presser-member including an attaching shank and a tread-portion having a needle opening, a support rigidly associated with said presser-member and rising higher than said shank, a cord-guiding leaf-spring secured at its upper end to said support at a point higher than the upper end of said shank and extending downwardly at an inclination to the vertical, said leaf-spring terminating within the needle opening in said presser-member and being deflectable by a conventional sewing machine needle.

ESTEBAN PRATO.
